US00D939091S

(12) **United States Design Patent** (10) **Patent No.:** **US D939,091 S**
(45) **Date of Patent:** **** Dec. 21, 2021**

(54) **TEETH CLEANING SYSTEM**

(71) Applicant: **ZeroBrush, Inc.**, Palo Alto, CA (US)

(72) Inventors: **Nidhi Pai**, Palo Alto, CA (US); **Ria Pai**, Palo Alto, CA (US); **Jason Hu**, San Jose, CA (US); **Akash Pai**, Palo Alto, CA (US)

(73) Assignee: **ZEROBRUSH, INC.**, Palo Alto, CA (US)

(**) Term: **15 Years**

(21) Appl. No.: **29/762,561**

(22) Filed: **Dec. 17, 2020**

Related U.S. Application Data

(63) Continuation of application No. 29/738,225, filed on Jun. 16, 2020, now Pat. No. Des. 908,223, which is a continuation of application No. 29/719,751, filed on Jan. 7, 2020, now Pat. No. Des. 890,350.

(57) **CLAIM**

The ornamental design for a teeth cleaning system, as shown and described.

DESCRIPTION

FIG. 1 is a front perspective view of a teeth cleaning system showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The dash-dot-dash broken lines illustrate boundaries that form no part of the claimed design. The broken lines illustrate structure or features that form no part of the claimed design.

1 Claim, 6 Drawing Sheets
